(57) **CLAIM**

The ornamental design for a bench, as shown and described.

DESCRIPTION

FIG. 1 is a front perspective view of a bench according to our new design;

FIG. 2 is a front/rear view thereof, it being understood that the front and rear views are identical;

FIG. 3 is a right side/left side view thereof, it being understood that the right side and left side views are identical; and, FIG. 4 is a top view thereof.

The bottom of the bench is plain and unornamented.
